(57) CLAIM

We claim the ornamental design for a coin holder for jewelry, as shown and described.

DESCRIPTION

FIG. 1 is a perspective frontal side view of the coin holder for jewelry of our new design, showing the appearance of the holder before it is added to a bracelet or wristband as it would be worn on a person's wrist or before it is added to a chain for a pendant for a necklace or before it is added to a pin.

FIG. 2 is a perspective back view of the coin holder for jewelry of FIG. 1.

FIG. 3 is a front view of the coin holder for jewelry of FIG. 1.

FIG. 4 is a back view of the coin holder for jewelry of FIG. 1.

FIG. 5 is a left side view of coin holder for jewelry of FIG. 1.

FIG. 6 is a right side view of the coin holder for jewelry of FIG. 1.

FIG. 7 is a top view of the coin holder for jewelry of FIG. 1.

FIG. 8 is a bottom view of the bracelet of FIG. 1.

FIG. 9 is a perspective view of the coin holder for jewelry opened to receive a coin.

FIG. 10 is another perspective view of the coin holder for jewelry of FIG. 1 positioned to show how it may be used on a wristband or bracelet. The wristband shown in broken lines is for illustrative purposes only and forms no part of the claimed design; and,

FIG. 11 is another perspective view of the coin holder for jewelry of FIG. 1 positioned to show how it as a pendant. The bar and ring for adapting the coin holder for jewelry for a pendant and shown in broken lines is for illustrative purposes only and forms no part of the claimed design.
